S. TRUSTMAN,
COMBINED PHONOGRAPH AND LAMP,
APPLICATION FILED NOV. 30, 1921.

Patented Dec. 12, 1922.

Solomon Trustman Inventor

By J. C. Thomas Attorney

Patented Dec. 12, 1922.

UNITED STATES PATENT OFFICE.

SOLOMON TRUSTMAN, OF DETROIT, MICHIGAN, ASSIGNOR OF ONE-HALF TO AMOS EMSLEY, OF DETROIT, MICHIGAN.

COMBINED PHONOGRAPH AND LAMP.

Application filed November 30, 1921. Serial No. 518,804.

To all whom it may concern:

Be it known that I, SOLOMON TRUSTMAN, citizen of the United States, residing at Detroit, county of Wayne, State of Michigan, have invented a certain new and useful Improvement in Combined Phonographs and Lamps, and declare the following to be a full, clear, and exact description of the same, such as will enable others skilled in the art to which it pertains to make and use the same, reference being had to the accompanying drawings, which form a part of this specification.

My invention relates to a combined phonograph and lamp,—shown in the accompanying drawings and more particularly described in the following specification and claims.

One of the objects of this invention is to provide a phonograph with a relatively long upright horn which serves as a lamp standard and support for the phonograph body carrying the usual turn table, tone arm and motor.

A further object of the invention is to provide for the adjustment of the horn and standard whereby the length of the horn may be regulated and the altitude of the lamp adjusted as required.

With the foregoing and other objects in view which will appear as the description proceeds the invention further resides in the combination and arrangement of parts and in the details of construction herein-after described and claimed, it being understood that changes may be made in the precise embodiment of the invention herein disclosed without departing from the spirit of the same.

In the drawings accompanying this specification:

Figure 1 is a perspective view of the device showing the hinged lamp shade raised to expose the turntable and tone arm of the phonograph, and also the lamp bulb mounted in a suitable socket carried by the top on which the turn table is mounted.

Figure 2 is a vertical longitudinal sectional view through the device showing the body of the phonograph with the tone arm connected with the vertical horn or lamp standard: and in dotted lines the body of the phonograph raised to increase the length of the horn and altitude of the lamp.

Referring now to the letters of reference placed upon the drawings:

A, denotes a vertically arranged horn which may be of any desired shape in cross section, on which is mounted a bowl-shaped chamber B provided with a tubular neck C 60 telescoping in the upper end of the horn or lamp standard. D, is a set screw or other suitable device, for securing the bowl-shaped chamber in its adjusted position. E, indicates the turn table of the phonograph and 65 F denotes a suitable motor for actuating the turn table,—which may be of the usual spring type or an electric motor as desired. G, indicates a crank for winding a spring actuated motor. H, denotes the usual 70 swinging tone arm connected by a throat I with the neck C. J, is a lamp bulb supported in a suitable socket on the underside of the bowl-shaped chamber B and back of the fringe K surrounding the latter. L, is 75 a lamp bulb mounted on a top or platform M above the brim of the bowl shaped chamber and adjacent to the record. N, is a lamp shade hinged to the platform.

When it is desired to change the record 80 the lamp shade N is raised as indicated in Figure 1 that the record may be removed or replaced upon the turn table,—the shade may be then lowered thereby softening the light from the bulb and modifying the 85 sound of the record.

As will be readily understood the sound waves are directed by the tone arm down through the throat into the vertical horn, escaping near the floor. The length of the 90 horn or altitude of the lamp standard may be increased by raising the telescoping neck extending into the upper end of the horn. When properly adjusted it may be secured by the set screw as shown in the drawing. 95

Having thus described my invention what I claim is:

1. A device of the character described consisting of a lamp and phonograph combined in a single unit, with the horn of the phonograph forming a supporting standard for the lamp and phonograph, a bowl-shaped member adapted to house the phonograph motor, having a projecting neck extending into the end of the horn and longitudinally adjustable therein, whereby the length of the horn may be adjusted and the altitude of the lamp regulated, a throat

within the bowl-shaped member connecting the tone arm of the phonograph with the projecting neck of the bowl, and means for securing the projecting neck in the end of 5 the horn when properly adjusted.

2. A device of the character described consisting of a combined lamp and phonograph unit, the horn of the phonograph forming a supporting standard for the unit, a bowl-shaped chamber adapted to house the phonograph motor, having a projecting neck extending into the end of the horn and longitudinally adjustable therein, a platform covering said bowl-shaped chamber, a motor housed in the bowl-shaped chamber, a throat within the bowl-shaped chamber connecting the tone arm of the phonograph with the projecting neck of the bowl, means for securing the projecting neck in the end 20 of the horn when adjusted, and a shade hinged to said bowl adapted to cover the phonograph and lamp.

3. In a device of the character described, a bowl-shaped chamber, a platform cover-

ing said chamber, a phonograph mechanism 25 including a tone-arm mounted thereon, a motor housed within the chamber, a lamp bulb mounted upon the platform and another lamp bulb located beneath the chamber to light the records when mounting or 30 replacing the same, a vertically disposed horn and standard extending downwardly from beneath the chamber, a neck extending downwardly from the chamber adapted to telescope with the horn whereby the length 35 of the horn may be adjusted and the altitude of the lamp regulated, a throat within the chamber connecting the neck with the tone arm and a hinged shade adapted to cover the several elements mounted upon the platform of the chamber.

In testimony whereof, I sign this specification in the presence of two witnesses.

SOLOMON TRUSTMAN.

Witnesses:

S. E. THOMAS,
IDA GOREN.
